UNITED STATES PATENT OFFICE.

ROBERT J. WILLIAMS, OF VINCENNES, INDIANA.

NUTMEG-GRATER.

SPECIFICATION forming part of Letters Patent No. 588,207, dated August 17, 1897.

Application filed February 12, 1897. Serial No. 623,047. (No model.)

To all whom it may concern:

Be it known that I, ROBERT J. WILLIAMS, a citizen of the United States, residing at Vincennes, in the county of Knox and State of Indiana, have invented certain new and useful Improvements in Nutmeg-Graters; and I do hereby declare the following to be a full, clear, and exact description of the invention, such as will enable others skilled in the art to which it appertains to make and use the same.

My invention relates to certain new and useful improvements in nutmeg-graters, the object being to provide an improved construction of sliding nutmeg-holder adapted to press the nutmeg into contact with the corrugated or roughened face of the grater, so that as the holder is slid back and forth longitudinally of the grater the nutmeg will be easily and quickly grated.

To this end my invention consists in providing a grater having a roughened face and an opening at one end thereof and a nutmeg-holder provided with flanges running in grooves on the grater and open at the inner side thereof, so that a nutmeg may be inserted through the said opening in the grater into the holder, and the said holder having a spring-pressed follower adapted to hold the nutmeg firmly pressed against the corrugated or roughened face of the grater, so that the entire nutmeg may be grated.

In the accompanying drawings, Figure 1 is a perspective view of a nutmeg-grater constructed in accordance with my invention. Fig. 2 is a cross-sectional view thereof, taken through the sliding nutmeg holder and grater; and Fig. 3 is a perspective view of the sliding nutmeg-holder removed from the grater.

Referring to the drawings, the letter A designates a grater consisting of an approximately semicircular-shaped piece of metal provided with a roughened or corrugated face B, formed by punching holes through the said face from the interior side thereof in the usual manner. The terminal edges of the side flanges c of the grater are bent inward to form a guideway d, which is closed by a stop-piece d' at each end thereof. The corrugated face of the grater is provided adjoining one end thereof with an opening e, through which the

nutmeg is inserted into the holder F, as hereinafter described.

The holder F consists of a metal casing of cylindric or other suitable form provided with a substantially semicircular base part G, 55 which extends across the corrugated or roughened face B. The side flanges h of the holder-base are coiled at their terminal ends h' to form side pieces, which are confined within and traverse the said guideways d of 60 the grater. The inner end of the holder or casing is open, so that when the said holder is in coincidence with the opening e of the grater a nutmeg may be inserted from the inner side of the grater into said holder. A 65 follower i is inclosed within the case of the holder and is attached to a stem k, which projects to the exterior through a tubular extension l on the closed head of the case and is provided on the exterior with a head or knob 70 k'. By means of this head or knob the spring-pressed follower may be drawn inward to permit of the insertion of the nutmeg.

In practice the holder containing the nutmeg is slid rapidly back and forth over the 75 corrugated face of the grater until the entire nutmeg has been grated or a portion of the same has been grated for use as desired. The spring-pressed follower keeps the nutmeg into contact with the said corrugated face until 80 the entire nutmeg has been thoroughly grated.

Having thus described the invention, what is claimed as new, and desired to be secured by Letters Patent, is—

A nutmeg-grater having a grating-face and 85 two side flanges formed integrally therewith, said flanges having their edges coiled inwardly to form guideways, stop-pieces closing said guideways at the ends thereof, and a nutmeg-holder provided with slides mov- 90 able in said guideways and adapted to abut against the stop-pieces to prevent disconnection of the holder from the grater.

In testimony whereof I have signed this specification in the presence of two subscribers. 95

ROBERT J. WILLIAMS.
